UNITED STATES PATENT OFFICE.

EINER, WILLIAM LARSEN, OF CHICAGO, ILLINOIS, ASSIGNOR TO WESTERN ELECTRIC COMPANY, INCORPORATED, OF NEW YORK, N. Y., A CORPORATION OF NEW YORK.

MECHANISM FOR SUPPORTING AND MOVING CIRCULAR OBJECTS.

Application filed September 16, 1924. Serial No. 738,112.

To all whom it may concern:

Be it known that I, EINER WILLIAM LARSEN, a citizen of the United States, residing at Chicago, in the county of Cook and State of Illinois, have invented certain new and useful Improvements in Mechanisms for Supporting and Moving Circular Objects, of which the following is a full, clear, concise, and exact description.

This invention relates to mechanisms for supporting and moving circular objects and more particularly to mechanisms for moving and supporting reels.

An object of the invention is to provide an improved mechanism for moving and supporting circular objects such as reels.

In accordance with some features of the invention there is provided a pair of rollers against which the peripheries of the heads of a supply reel may be placed and a pair of lifting arms pivoted eccentrically with respect to the center of the reel and interconnected at their ends by a rod carrying idlers which are adapted to also engage the peripheries of the heads of the reel and co-operated with rollers to lift and support the reel. The lifting arms are equipped with counterweights and springs, which facilitate their operation.

Other objects and advantages of the invention will more fully appear from the following detailed description taken in connection with the accompanying drawings which illustrate one embodiment thereof, and in which

Fig. 1 is an end view of a multi-unit braiding machine embodying the features of the invention;

Fig. 2 is a fragmentary front view of the structure shown in Fig. 1;

Fig. 3 is a diagrammatic view illustrating the manner in which the reel is lifted and lowered, and

Fig. 4 is a fragmentary sectional view taken on the line 4—4 of Fig. 1, showing the improved take-up reel driving mechanism.

In order to illustrate the invention the accompanying drawings show an embodiment of the invention applied to a multi-unit braiding machine, but it is to be understood that the invention may be used to advantage in many other applications and is to be limited only in so far as defined by the appended claims.

Referring now to the drawings in detail

in which like reference numerals designate similar parts throughout the several views, 10 denotes a frame of a multi-unit braiding machine particularly adapted for covering a cable core. Rotatably mounted on the upper part of the frame 10 is a power driven capstan 11 (Fig. 1) which is adapted to draw a cable core 12 from a supply reel 13 through a braiding head 14. The cable core 12 after it leaves the capstan 11 passes through a distributor 27 and is taken up by a power driven take-up reel 15.

The supply reel 13 and the take-up reel 15 are suitably positioned side by side in line with and directly under the capstan 11 and near the floor line where they may be easily lifted to their operative position or lowered from the operative position and removed from the machine. The peripheries of the two heads of the supply reel 13 engage a pair of rollers 16—16 and the peripheries of the two heads of the take-up reel 15 engage a pair of rollers 17—17. The rollers 16—16 and 17—17 are carried on a shaft 18 driven by a pulley 25, actuated by any suitable means (not shown), and suitably journaled in the lower part of the frame 10. The rollers 16—16 as best shown in Fig. 4 are rotatably mounted on ball bearings 19 carried by the shaft 18. Each of the rollers 17—17 (Fig. 4) surround a plurality of telescoped sleeves 20, 21 and 22 the sleeve 20 being shown keyed to the roller 17 and the sleeve 22 being shown splined to a driving element 23 which is keyed to the shaft 18. It will be noted that the rollers 17—17 are preferably made of phenolized canvas, and that although each of the rollers 17—17 surround only three telescoped sleeves, as best shown in Fig. 4.

Secured to the frame 10 are brackets 30—30 (Fig. 1) to the ends of which are pivotally mounted arms 31—31 and arms 32—32. In order to simplify the structure, one of the brackets provides a common pivot for two arms 31 and 32. The free ends of arms 31—31 are connected by a rod 33 and the free ends of the arms 32—32 are connected by a rod 34. Rotatably mounted on the rod 33 are a pair of idlers 35 and 36 which are adapted to engage the peripheries of the heads of the supply reel 13. Likewise rotatably mounted on the rod 34 are a pair of idlers 37 and 38 which are adapted to engage the peripheries of the heads of the

take-up reel 15. The rod 33 serves to maintain the supply reel lifting arms 31-31 rigidly in a parallel position relative to each other and also provides a means whereby both arms may be lowered and raised simultaneously as will be more fully described hereinafter. Similarly the rod 34 serves to maintain the take-up reel lifting arms 32-32 rigidly in a parallel position relative to each other and also provides a means whereby these two arms may be lowered and raised simultaneously as will likewise be more fully described hereinafter. The centers upon which the arms 31-31 and 32-32 pivot are in alignment and are eccentric to and above the centers of the reels.

Secured to one of the brackets 30, intermediate its ends, is a pin 40, and secured to one of the arms 31 is a pin 41, the two pins being connected by a tension spring 42. Likewise secured to another of the brackets 30 is a pin 43, and secured to one of the arms 32 is a pin 44, the two pins 43 and 44 being also connected by a tension spring 45. Attached to the arms 31-31 are counterweights 46-46, and attached to the arms 32-32 are counterweights 47-47. Located in the ends of the arms 31-31 are studs 48-48 and located in the ends of the arms 32-32 are studs 49-49; the studs 48-48 and 49-49 serving to space the arms 31-31 and 32-32, respectively, from the floor. These studs are held in place in the ends of the arms by set screws 52.

The operation of this mechanism is as follows: The reels 13 and 15 are each first rolled along the floor into a receiving position, similar to the position that reel 13 is shown in Fig. 1, with the peripheries of the heads of the reel 13 engaging the rollers 16-16 and the peripheries of the heads of the reel 15 engaging the rollers 17-17. During the time that the reels 13 and 15 are in their respective receiving positions the lifting arms 31-31 and 32-32 are in positions similar to the position of arm 31 as shown in Fig. 1. It is, of course, obvious that while the reel receiving positions were vacant, the arms 31-31 and 32-32 were drawn upwardly and maintained in their uppermost or normal positions by the counterweights 46-46 and 47-47, respectively. Furthermore, once the springs 45 and 42 are above the pivots of the arms 31-31 and 32-32 they will aid the counterweights in drawing the arms upwardly (Fig. 1).

After the reels 13 and 15 have been placed in their respective receiving or inoperative positions the rods 33 and 34 are drawn forwardly and downwardly, by the operator, carrying arms 31-31 and 32-32, respectively, with them. During the downward passage of the arms 31-31 and 32-32 the idlers 35 and 36 will make contact with the

peripheries of the heads of the reel 13 and the idlers 37 and 38 will make contact with the peripheries of the heads of the reel 15 at about the time the arms 31-31 and 32-32 assume their horizontal positions. After this time and from thereon until the studs 48-48 and 49-49 touch the floor the idlers exert a camming effect on the heads of the reels 13 and 15 which with the aid of the rollers 16-16 and 17-17, respectively, causes the reels 13 and 15 to be raised until they rest upon the rollers 16-16 and 17-17, respectively, and the associated idlers, 35, 36, 37, and 38. The weight of the arms aided by the resilience of the associated springs 45 and 42 will ordinarily be sufficient for causing the arms to lift the reel once the arms have passed their horizontal positions. When a fully loaded supply reel 13 is being raised it may be necessary to assist the downward action by a small amount of manual pressure upon the rod 33. The diagrammatic view shown in Fig. 3 shows clearly the manner in which the arms 32 cause the take-up reel 15 to be raised, but it is to be understood that the supply reel 13 is raised in identically the same manner. In order to effect the above described raising and lowering of the reels 13 and 15 it is, of course, apparent that the pivots of arms 31-31 and arms 32-32 be eccentric to and above the centers of the reels.

It is, of course, obvious that the springs 45 and 42 when above the pivots of the arms 31-31 will aid in maintaining the arms in their inoperative positions and when below the pivots will aid in maintaining the arms in their respective lowered or operative positions.

The studs 48-48 and 49-49 in addition to serving to space the arms 31-31 and 32-32, respectively, from the floor also determine the distance which the reels 13 and 15 may be raised, for by loosening the set screws 52 and moving the studs vertically the downward travel of the arms may be varied, which results in a relative change in the distance the reels may be raised.

After the reels 13 and 15 have been raised to their respective operating positions the cable core 12 is fed from the reel 13, through the braiding head 14, around the capstan 11, through the distributor 27, and onto the take-up reel 15 as best shown in Fig. 2. The cable core in being withdrawn from the supply reel 13 by the capstan 11 causes the supply reel to revolve; the heads of the supply reel 13 rolling freely on the rollers 16-16, which through the ball bearings 19, are permitted to rotate loosely on the shaft 18 in the same direction in which the shaft is turning.

The rollers 17 are actuated by the sleeves 20 which are frictionally driven by the associated sleeves 21 actuated by the shaft

18 as is clearly shown in Fig. 4. The rollers 17-17 engage the heads of the reel 15, driving it in the same direction in which the reel 13 is revolving and causing the cable 5 core 12, after it has left the capstan, to be taken up on the reel 15.

It has been found that the pull on the cable core 12 by a take-up reel driven by any usual type of friction drive decreases as the 10 cable core is wound in layers on the reel, due to the fact that the driving torque remains unchanged, causing a relative decrease in tension on the cable core.

In order for the capstan 11 to properly 15 draw the cable core 12 through the braiding head 14 it is essential that the tension on the cable core between the capstan 11 and the take-up reel 15 be substantially uniform at all times.

20 The desired conditions may be accomplished by employing the structure described above since as the cable core is wound on the reel 15 the weight pressing down on the rollers 17-17 and the idlers 25 37 and 38 increases, causing a closer frictional contact between the driving rollers and the heads of the reel, thereby resulting in a relative increase in the driving force. This increase in the driving force causes a 30 proportional increase in the torque thereby increasing the pull on the core and causing the tension thereon to remain substantially unchanged.

Furthermore, it will be noted that any 35 slippage in the driving parts takes place inside of the rollers 17-17 between the sleeves thereof and not between the peripheries of the heads of the reel and the peripheries of the rollers as heretofore. This has 40 been found very advantageous, inasmuch as the slipping between the rollers 17-17 and the heads of the reel might in some cases cause flat spots to be worn on the peripheries of the heads of the reel.

45 To replace either reel 13 or the reel 15 it is only necessary to raise either the rod 33 or the rod 34 to its uppermost position, the reel being lowered to the floor gradually as the rod is raised.

50 This invention is advantageous in many respects, but its chief advantage is in that it provides a simple, inexpensive mechanism whereby heavy cumbersome reels may be easily and quickly elevated from the reel receiving position to the operative position on a strand working machine and lowered back to the receiving position.

What is claimed is:

60 1. In a mechanism for moving and supporting a circular object, rollers for engaging the object, arms movable in an arcuate path with respect to the center of the object and idlers associated with the arms for cooperating with the rollers in moving and supporting the object.

2. In a mechanism for moving and supporting a circular object, an element for engaging the object, means pivoted eccentrically with respect to the center of the object and movable in an arcuate path to engage the periphery of the object, to move the object, means for maintaining the pivoted means in an inoperative position, and resilient means associated with the last mentioned means for aiding in maintaining the pivoted means in an inoperative position and also for facilitating the movement of the pivoted means into an operative position.

3. In a mechanism for moving and supporting a circular object, an element for engaging the object, means pivoted eccentrically with respect to the center of the object and movable in an arcuate path to engage the periphery of the object and cooperating with the element in moving the object, means for maintaining the pivoted means in an inoperative position, means for aiding in maintaining the pivoted means in an inoperative position and to also aid in maintaining the pivoted means in an operative position, and means for controlling the distance the object is moved.

4. In a mechanism for moving and supporting a circular object, an element for engaging the object, a pair of arms pivoted eccentrically with respect to the center of the object and movable in an arcuate path, a member interconnecting the ends of the arms to maintain them in a parallel relation, and means rotatably mounted on the member for engaging the periphery of the object to move the object.

5. The combination with a strand working mechanism of a mechanism for moving and supporting a strand reel comprising rollers for engaging the reel, arms movable in an arcuate path with respect to the center of the reel, and idlers associated with the arms for cooperating with the rollers in moving and supporting the reel.

6. In a mechanism for lifting a circular object, an element for engaging the periphery of the object, and means cooperating with said element for moving the object about a fulcrum on the periphery thereof.

7. In a mechanism for lifting a circular object, an element for engaging the periphery of the object, and resiliently controlled means cooperating with said element for moving the object about a fulcrum on the periphery thereof.

8. In a mechanism for lifting reels and the like, an element for engaging a head of said reel, and means movable in an arcuate path for moving said element to elevate said reel.

9. In a mechanism for lifting reels and the like, an element for engaging the periphery of said reel, means movable in an arcuate

- ate path for moving said element and causing its engagement with said reel, and resilient means cooperating with said means for aiding the movement of said element.
- 5 10. In a mechanism for lifting reels and the like, an element for engaging a head of said reel, means movable in an arcuate path for moving said element to elevate said reel, and means for limiting the movement 10 of said means and thereby the elevation of said reel.
11. In combination with a braiding machine, an attachment for lifting a material supply reel comprising an element having 15 a plurality of positions, and means cooperat-
- ing with said element for causing its engagement with the periphery of said reel and the lifting thereof upon its continued movement.
12. In combination with a braiding machine, an attachment for lifting a material supply reel comprising a pair of oppositely disposed arms, and means associated with said arms and effective upon their movement for engaging the peripheral edge of 25 said reels to lift the same.

In witness whereof, I hereunto subscribe my name this 3 day of Sept. A. D., 1924.

EINER WILLIAM LARSEN.
